UNITED STATES PATENT OFFICE.

WILLIAM J. LANE, OF POUGHKEEPSIE, NEW YORK.

DESIGN FOR A FRAME FOR DOOR-HANGERS.

SPECIFICATION forming part of Design No. 21,006, dated August 18, 1891.

Application filed May 2, 1890. Serial No. 350,411. Term of patent 14 years.

To all whom it may concern:

Be it known that I, WILLIAM J. LANE, a citizen of the United States, residing at Poughkeepsie, in the county of Dutchess and State of New York, have invented a new and original Design for a Frame for Door-Hangers, of which the following is a specification, reference being made to the accompanying photograph forming a part thereof.

10 My design is shown in three figures, Figure 1 representing a front view, Fig. 2 a side view, and Fig. 3 a top view.

15 My design presents the appearance of an oblong body with rectangular corners, with a parallel slot in the top portion and two angular slots in the bottom portion. The inner lines of the two sides 1 1^a of said body appear to be curved backward at 2 2 and straight at 3, thereby forming angles at 4 4, with one side 20 of each angle curved. The outer lines also appear to be curved backward at 5 5 and straight at 6, all as shown in Fig. 2. The top and bottom lines 7 8 of the top of said body appear to be parallel in Fig. 1 and curved 25 outwardly at 9 9 and straight and parallel at 10 10, Fig. 3. On the top of said body in Fig.

1 there appears to be two parallel lines 11 11, joined at their ends by the curved lines 12 12. The top and bottom lines 13 14 of the bottom of said body appear to be parallel over most 30 of their length. At the left-hand corner of the bottom of the design the top line 13 is drawn at an angle to the line 14. At the bottom of said body there appears to be two sets of parallel lines 15 15, the sets joined at one 35 end by the curved lines 16 16. There also appears a line 17 parallel to the lines 13 14 and at right angles to inner and outer lines of the ends at the side 1^a of the body. At the two upper corners of the design there appears to be two convex circular projections 40 20, at the lower left-hand corner one convex circular projection 21 and just above the lower right-hand corner one convex circular projection 22.

45

I claim—

The design for a door-hanger frame, substantially as herein shown and described.

WILLIAM J. LANE.
